Patented May 11, 1915.

UNITED STATES PATENT OFFICE.

CHARLES C. JAMES, OF NEW YORK, N. Y.

STOPPING DEVICE FOR TALKING-MACHINES.

1,130,421.

Specification of Letters Patent. Patented May 11, 1915.

Application filed October 10, 1912, Serial No. 725,074. Renewed April 2, 1915. Serial No. 18,640.

To all whom it may concern:

Be it known that I, CHARLES C. JAMES, a citizen of the United States, residing in the city, county, and State of New York, have 5 invented certain new and useful Improvements in Stopping Devices for Talking-Machines, of which the following is a specification.

My invention relates to a stopping device 10 for talking machines and may be used in connection with various types of such machines upon the market, to wit, the Columbia, the Edison, the Victor, and other types. The object of my invention is to produce 15 a stopping device which will stop the operation of the machine by co-operation with the end of the sound record.

A further object of my invention is to produce a device which is applicable to various 20 lengths of sound records.

Further, to produce a device which is adjustable to various sizes of machines.

A further object is to produce a device wherein the action of the stopping means 25 will not cause the reproducer to jump out of the groove.

A further object of my invention is to provide an automatic means for feeding the stylus in coincidence with the sound groove 30 without employing the stylus of the sound groove for such a feeding.

These and other objects, which will appear as the description proceeds, I attain by means of the devices whereof the description is hereinafter contained and which 35 are illustrated in the accompanying drawing; wherein—

Figure 1 is a plan view of a talking machine having my improvement attached; 40 Fig. 2 is a side elevation of the device shown in Fig. 1, the parts being broken away; Fig. 3 is a detail elevation of a brake-shoe forming part of my invention; Fig. 4 is an end view thereof looking from the left in 45 Fig. 3; Figs. 5, 6 and 7 are detail views of an abutment connected to the reproducer carrier; and Figs. 8 and 9 are respectively plan views and section of the connection between the rotary brake shaft and the axis.

I have illustrated my invention as applied 50 to a Victor talking machine for convenience, but it is not necessarily limited in its use to such machine.

According to my invention, a pair of mov-

able members is employed, one of which is a 55 brake-carrying member and is given movement, in this case rotary movement, from the record carrier. This member, which is lettered A, has a capacity for slight longitudinal movement whereby the brake B is 60 brought into contact with a movable part of the machine. An abutment C is supported from the movable reproducer carrier, and in this case the movable part of the tone-arm, so that as said arm moves with the stylus 65 in following the sound record the abutment likewise moves. The abutment C has a threaded connection with the shaft carrier A and the parts are so adjusted, proportioned, and operated that the longitudinal movement given to the abutment by reason of the rotation of the shaft, will coincide with the swinging movement given to the abutment by the movement of the reproducer carrier. Swivel and pivoted connections of 70 the members permit these movements. It will be seen, therefore, that so long as the reproducer carrier is moved by the sound record and the rotary shaft is moved by the record carrier, that no longitudinal movement of the shaft will take place. When, however, the stylus reaches the end of the sound groove the movement of the reproducer carrier will cease, whereupon the abutment will become fixed and continued rotation of the brake shaft will cause a longitudinal movement of the said shaft whereupon the brake B will gradually have braking contact with the movable part of the machine and its operation will be stopped. 85

The foregoing is an outline of the principal parts of the apparatus. A more detailed description of the particular mechanism employed and of the advantages derived from the construction illustrated will 90 now be given.

The said improvements are illustrated in connection with a talking machine of usual type, wherein the record 1 is supported upon a turn-table 2 having an axis 3 constituting 100 the record carrier, and the reproducer carrier comprises a tone-arm 4 having a movable portion 5 with the usual goose-neck 6 terminating in the stylus 7, which operates in the usual manner by contact with the concentric sound groove in the record 1, whereby the reproducer carrier 5, 6, 7 has a swinging movement from the periphery of the

disk to its center. The length of the grooves constituting the sound record varies in different disks, and my invention is adapted to stop the operation of the talking machine 5 when the end of the sound record is reached, whether that end be adjacent the axis or at any point intermediate the periphery and the axis.

The brake-operating device is illustrated 10 as a shaft A which is shown as having a rotary movement, likewise as being capable of a slight longitudinal movement for the purpose of applying a brake and releasing the same, and further as having a movement 15 about its pivotal axis for the purpose of permitting the movement in an arc of a circle of the abutment C. The said shaft A on its inner end is mounted between the arms of a bracket a (seen in detail in Figs. 20 8 and 9). This bracket has a cut-away portion a^1 through which the shaft A passes and in said cut-away portion is a gear a^2 fixed on said shaft. Upon the axis 3 is mounted a removable worm carrier a^3 . 25 This has upon its underside oppositely disposed notches a^4 which are adapted to receive the usual pins a^5 with which the axis 3 is customarily equipped for the purpose of driving the turn-table 2 and the said 30 worm carrier upon its upper side has corresponding projections a^6 which are adapted to drive the turn-table. Upon this worm carrier is a peripheral worm a^7 . This serves the function of supporting the 35 bracket a by revolving in an internal groove a^8 therein and also of engaging and turning the gear a^2 and the rotary shaft A. It will be perceived that in Fig. 8 the gear a^2 is shown at the left hand side of the opening 40 a^1 in which position the brake B will be out of contact with the movable part of the machine with which it engages. The worm a^7 has a clockwise movement, as illustrated in Fig. 8, and the friction of the worm upon 45 the gear causes the shaft to assume this position which it will retain as long as the parts are in operation. The space a^1 , however, is so much wider than the gear a^2 that when the brake is brought into operation 50 by the means hereinafter described, the shaft A is permitted a longitudinal movement sufficient to apply the brake.

Fixed upon the movable part 5 of the reproducer carrier, to wit, the movable part 55 of the tone-arm, is an arm D which is clamped thereon so as to be removable therefrom by means of the band d having flanges d^1 through which pass the clamping screw d^2 . From this arm depends the abutment 60 C. This arm D is fixed in position upon the movable part 5 of the tone-arm, whereby as the said tone-arm swings on its pivot by reason of the travel of the stylus 7 in the sound record, the arm D will have a cor-

responding movement. Upon the outer end 65 of the arm D is the abutment C. This abutment at its lower end is provided with oppositely disposed slots e , through which slots passes the rotary brake shaft A. Means are provided for causing an engagement 70 between the said shaft and the abutment, and as illustrated such means comprise a thread a^{10} upon the said shaft and a corresponding threaded engaging member E in the abutment. The abutment is made 75 hollow and within it slides a plug e which is perforated at e^1 for the passage of the rotary shaft A and which is spring-pressed downwardly by spiral springs e^2 . The plug e carries the knife-edged member E, which 80 constitutes the thread engaging member, and slides in a bore of the plug e and is spring-pressed downwardly by spiral spring e^3 . The bottom wall of the abutment C 85 may be pressed inwardly as at c^1 to retain the said parts from dropping out of the said abutment.

Fig. 1 in dotted line position shows the 90 position occupied by the arm D and shaft A at the end of the sound groove, and from this it will be seen that the shaft A is capable of movement about its pivotal supporting bracket a for the purpose of accommodating itself to the varying lateral positions of the abutment C, and for this reason 95 likewise the swivel connection between the shaft and the said abutment is provided.

It will be observed that the threaded portion a^{10} of the shaft A extends a portion 100 only of its length and that a portion is plane or unthreaded. It is intended that the plane portion of the said shaft shall correspond in length to the minimum length 105 of the sound record as the knife edge will slide easily over the unthreaded part of the said shaft, and it is desired that the threaded part shall be as long as will ever be required for any sound record no matter how short. The brake B is composed of a braking pad b which I prefer to make of some clinging material, and for this purpose I have found sponge rubber well adapted. This brake is mounted upon an arm b^1 , which in turn is perforated to receive the 110 shaft A, upon which the said arm is adapted to slide. An adjusting sleeve F is mounted upon the shaft A outside of the brake arm b^1 and has a split spring shank f^1 whereby it will be held in adjusted position and will 115 prevent an outer movement of the brake B when it is desired to apply the same.

I have illustrated the brake as engaging a moving part of the machine, in this case the periphery of the turn-table 2, which 120 turns in the direction of the arrow in Fig. 1, and this I regard the most desirable point of engagement for the said brake. I do

not, however, wish to limit myself to an engagement of the brake at this point, nor to the particular construction of brake illustrated as other types of brakes operated by the longitudinal movement of the shaft could be employed, whether they engaged the periphery of the turn-table or some other moving part. It will be observed that this brake has a pull when in operation which is substantially perpendicular to the longitudinal axis of the brake shaft A. I have discovered that when the brake is applied in line with the longitudinal axis of the said brake shaft A that the action of the brake is irregular, and that it has a tendency to cause the stylus to jump out of the sound groove and prevent the operation of the brake. By providing the arm d, however, whereby the stress of the brake is at substantially right angles to the axis of the said brake shaft, and by providing a brake substance, which is of clinging material, I have found that the jumping effect upon the stylus is entirely overcome and that the machine is brought to a complete stop gradually.

It will be perceived that my improved brake device may be applied upon a phonograph without further change therein than the addition of these parts, and such addition is effected by simply clamping the arm D upon the tone-arm and by placing the worm gear a² and bracket a upon the axis 3. The worm gear will thereupon be turned by the pins 10, with which such axis is customarily provided, and will in turn rotate the turn-table 2 by means of the pins a⁶ which lie in corresponding grooves provided in such turn-tables.

40 I prefer to provide the brake K with a pad b² as illustrated in Fig. 4, which is adapted to slide upon a fixed part of the apparatus and to regulate the movement of the brake and make the same uniform and 45 to hold the brake in position against the surface to which it may be applied.

The operation of my improved device is as follows:—The brake B will be adjusted so that the braking material b will just clear 50 the outer edge of the turn-table when the rotary shaft A is in the position illustrated in Fig. 1. The movable part of the tone-arm will be moved to its extreme position to enable the stylus 7 to enter the outer part 55 or beginning of the sound record. This will cause the abutment C to slide over the end of the brake shaft A, and for this purpose the contact member E will ride over the thread and will slide down the plane portion of the said shaft to the proper point. 60 This will cause a rocking or turning of the shaft A about its pivot a, as illustrated in dotted lines in Fig. 1. The goose-neck will be swung slightly outside of the sound

groove and then brought inwardly to exact 65 register therewith, and this outward movement will cause the brake to be released from the turn-table. This is of importance if the machine previously had the brake applied as it will automatically release it. A 70 movement of the reproducer carrier toward the axis 3 as the record is turned will cause a corresponding movement of the abutment C toward the outer end of the shaft A. The shaft A is rotated at a greatly reduced rate 75 by means of the worm gear so that its peripheral speed at the point of contact with the member E is such as would cause the abutment C to travel at the same rate at which the reproducer carrier causes it to 80 travel, and thereby the said motions are equalized and neither will affect the other, because it will be apparent that if the said shaft moves faster than the abutment it will apply the brake, whereas if it moves slower 85 it would exercise a retarding effect upon the reproducer carrier. When the travel of the movable arm has progressed so far that the stylus has arrived at the end of the sound groove, the movement of the abutment C will cease and the side wall of the sound groove will constitute a stop which will prevent further movement of the said stylus and consequently will hold the abutment C in its fixed position. Thereupon a 90 continued rotation of the shaft A from the axis 3 will cause the screw-thread, acting in conjunction with the screw-contact member E, to force the shaft A inwardly or toward the axis. The play of the gear a² will permit a sufficient movement of this shaft inwardly to cause the braking material b to 95 be applied to the periphery of the turn-table 2. This application will be gradual 100 and will gradually slow up the rotation of the turn-table until the same is completely stopped.

I prefer to operate the shaft A from the axis 3 as the said axis has a definite position and is of certain size, whereas the turn-table and other moving parts of the machine are of variable sizes and thereby cause different rates of speed which require a different proportion of gears to effect the necessary reduction of the shaft A to correspond to the speed of the arm D.

The threaded part of the brake shaft may be made sufficiently long to feed the reproducer throughout its engagement with the sound record grooves and to the point where the braking action begins. Under such circumstances the braking device has the further incidental and important function of the threaded part of the reproducer brake shaft, through its connection with the reproducer carrier, providing a means whereby the stylus may be fed forward without bearing upon the side walls of the grooves

for this purpose, and whereby the wear upon the groove is prevented and an absolute feed maintained irrespective of any wear or inequality upon the wall of the groove.

5 My invention is not necessarily limited to the exact proportion and arrangement of the parts shown, as the same may be varied and other parts substituted therefor and equivalent devices employed within the limits of the appended claims.

10 What is claimed is:—

15 1. A stopping device for machines, comprising a rotatable shaft adapted to be moved longitudinally, a brake shoe movable with said shaft, a rotary part of the machine to which said shaft is rotatably connected, an abutment having a threaded engagement with said shaft, a traveling part of the machine, means for connecting said 20 abutment thereto, whereby said abutment may be moved, and said abutment being adapted when stationary to cause movement of said shaft whereby the brake shoe is forced into engagement with a moving part 25 of the machine.

2. A stopping device for machines, comprising a rotatable shaft adapted to be moved longitudinally, a brake shoe movable with said shaft and adjustable thereon, a 30 rotary part of the machine to which said shaft is rotatably connected, an abutment having a threaded engagement with said shaft, a traveling part of the machine, means for connecting said abutment thereto 35 whereby said abutment may be moved, and said abutment being adapted when stationary to cause movement of said shaft whereby the brake shoe is forced into engagement with a moving part of the machine.

40 3. A stopping device for machines, comprising a rotatable shaft adapted to be moved longitudinally, a brake shoe movable with said shaft, a rotary part of the machine to which said shaft is rotatably connected, an abutment having a swiveled member engaging a thread on said shaft, a traveling part of the machine, means for connecting said abutment thereto whereby said abutment may be moved, and said abutment 45 being adapted when stationary to cause movement of said shaft, whereby the brake shoe is forced into engagement with a moving part of the machine.

45 4. A stopping device for machines, comprising a rotatable shaft having a threaded portion and a plane portion and adapted to be moved longitudinally, a brake shoe movable with said shaft, a rotary part of the machine to which said shaft is rotatably connected, an abutment longitudinally movable along said shaft and adapted to slide 50 on the plane part thereof and to engage the threaded part, a traveling part of the machine, means for connecting said abutment thereto whereby said abutment may be

50 moved, and said abutment being adapted when stationary to cause movement of said shaft whereby the brake shoe is forced into engagement with a moving part of the machine.

55 5. A stopping device for machines, comprising a rotatable shaft adapted to be moved longitudinally, a brake shoe connected to said shaft so as to move therewith and supported thereon so as to have a pull when 60 braking substantially perpendicular to the axis of said shaft, a rotary part of the machine to which said shaft is rotatable connected, an abutment having a threaded engagement with said shaft, a traveling part 65 of the machine, means for connecting said abutment thereto whereby said abutment may be moved, and said abutment being adapted when stationary to cause movement of said shaft whereby the brake shoe is forced into engagement with a moving part 70 of the machine.

75 6. A stopping device for machines, comprising a rotatable shaft adapted to be moved longitudinally, a brake shoe movable 80 with said shaft, a rotary part of the machine to which said shaft is rotatably connected, an abutment having a threaded engagement with said shaft, a traveling part of the machine, means for connecting said abutment 85 thereto whereby said abutment may be moved, and said abutment being adapted when stationary to cause movement of said shaft whereby the brake shoe is forced into engagement with a moving part 90 of the machine.

95 7. A stopping device for machines, comprising a rotatable shaft adapted to be moved longitudinally, a brake shoe mounted upon said shaft and adjustable with relation 100 thereto and adapted to engage a moving part of the machine, a rotary part of the machine to which said shaft is rotatably connected, a traveling part of the machine, an arm adapted to be fixed thereon, an abutment carried by said arm and having a threaded engagement with said shaft, said parts being so constructed that the movement of said abutment is at the same rate as the movement of said abutment caused 105 by the rotation of said shaft, and whereby as the movement of said arm connected to said traveling part ceases the abutment becomes fixed in position and the rotation of said shaft causes a longitudinal movement 110 thereof and operates the brake shoe.

115 8. A stopping device for machines, comprising a rotatable shaft adapted to be moved longitudinally, a brake shoe mounted upon said shaft and adjustable with relation 120 thereto and adapted to engage a moving part of the machine, a rotating part of the machine to which said shaft is rotatably connected, a traveling part of the machine, an arm adapted to be fixed there- 125

on, an abutment carried by said arm and having a swiveled engagement with said shaft, a spring pressed member on said abutment engaging a thread on said shaft whereby said threaded connection may yield in setting, said parts being so constructed that the movement of said abutment is at the same rate as the movement of said abutment caused by the rotation of said shaft and whereby as the movement of said arm connected to said traveling part ceases the abutment becomes fixed in position and the rotation of said shaft causes a longitudinal movement thereof and operates the brake shoe.

9. A stopping device for machines, comprising a rotatable shaft adapted to be moved longitudinally, a brake shoe mounted upon said shaft and adjustable with relation thereto and adapted to engage a moving part of the machine, a rotary part of the machine to which said shaft is rotatably connected, said rotating means being adapted to engage said rotary part in such manner that said rotary part exerts a longitudinal pressure on said shaft whereby said brake shoe is maintained out of operation, a traveling part of the machine, an arm adapted to be fixed thereon, an abutment carried by said arm and having a threaded engagement with said shaft, said parts so constructed that the movement of said abutment is at the same rate as the movement of said abutment caused by the rotation of said shaft, and whereby as the movement of said arm connected to said traveling part ceases the abutment becomes fixed in position and the rotation of said shaft causes a longitudinal movement thereof and operates the brake shoe.

10. A stopping device for machines, comprising a rotatable brake shaft, a pivotal support therefor, permitting longitudinal movement of said shaft, a gear on said shaft and a worm for driving said gear adapted to engage the upper end of a shaft of the machine, an abutment having a threaded engagement with the brake shaft, a traveling part of the machine by which said abutment is adapted to be moved, said abutment being adapted to become fixed when said traveling part ceases to move it and to serve as a fixed abutment for said shaft, whereby further rotation of the shaft will cause a longitudinal movement thereof, and a brake shoe on said shaft adapted to engage a moving part of the machine and stop the same.

11. A stopping device for machines, comprising an abutment, a traveling part of the machine adapted to move said abutment, a rotatable shaft a rotary part of the machine adapted to rotate said shaft, a stop device adapted to be actuated by said shaft, and a swiveled connection between said shaft and abutment comprising a spring pressed mem-

ber in said abutment adapted to engage a threaded part of said shaft and to pass over the same in adjusting.

12. A stopping device for machines, comprising an abutment, a traveling part of the machine adapted to move said abutment, a rotatable shaft a rotary part of the machine adapted to rotate said shaft, a stop device adapted to be actuated by said shaft, and a swiveled connection between said shaft and abutment comprising slots in said abutment through which said shaft passes, a rotary spring pressed plug in said abutment and a spring pressed pointer in said plug adapted to engage a threaded part of said shaft, and so to pass over the same in adjusting.

13. A stopping device for machines, comprising a rotatable shaft having a longitudinal movement a rotary part of the machine adapted to rotate said shaft, a stop device adapted to be actuated by said shaft, an abutment therefor and a traveling part of the machine adapted to move said abutment, said abutment becoming fixed when said traveling part ceases to move the same and serving to move said shaft, a thread on said shaft adapted to engage the abutment, and said shaft having a plane portion corresponding in length to the extent said machine is desired to run without being stopped.

14. A stopping device for machines, comprising a rotatable shaft having a longitudinal movement, a rotary part of the machine adapted to rotate said shaft, comprising a bracket adapted to be fixed to said shaft and to be pivotally supported on said rotary part, a gear on the shaft, a worm engaging said gear and adapted to engage said rotary part, a brake on the shaft and means adapted to move said shaft longitudinally and means adapted to temporarily compensate for the action of said means to move said shaft longitudinally, longitudinal movement of said shaft being adapted to apply the brake.

15. A stopping device for machines, comprising a rotatable shaft having a longitudinal movement, a rotary part of the machine adapted to rotate said rotary part, a brake shoe supported from said shaft and having a pull in operation substantially perpendicular to the axis of said shaft, and a traveling part of the machine and means connected thereto adapted to move said shaft longitudinally to apply the brake.

16. A stopping device for machines, comprising a rotatable shaft having a longitudinal movement, a rotary part of the machine adapted to rotate said shaft, a brake shoe supported from said shaft and having a pull in operation substantially perpendicular to the axis of said shaft, said brake shoe being formed of clinging material and a pad adapted to slide over a fixed part of the

apparatus and control the action of said brake, a traveling part of the machine and means under the control thereof adapted to move said shaft longitudinally to apply the brake.

17. A device of the character described, comprising a brake, a brake shaft, a rotary part of a machine, adapted to rotate said brake-shaft, said shaft having an additional brake controlling movement, an abutment a traveling part of the machine adapted to move said abutment, said abutment having a connection with said shaft, means whereby said abutment causes said shaft to have an additional brake controlling movement when the traveling part ceases to move the same.

18. A stopping device for machines or the like, comprising a rotatable shaft adapted to have an additional brake controlling movement, a brake shoe controlled by said shaft, a rotary part of the machine adapted to rotate said shaft, an abutment having an engagement with said shaft permitting relative movement, a traveling part of the machine adapted to temporarily move said abutment, and said abutment being adapted when stationary to serve as a fixed abutment for said shaft, whereby a continued movement of the shaft will cause an additional brake controlling movement of said shaft.

19. A stopping device for machines, comprising a rotatable brake shaft, a stop device adapted to be actuated by said shaft, a shaft supporting bracket, having an opening therein through which said shaft passes, a gear fixed on said shaft in said opening, a rotatable part of a machine, a worm carrier removably mounted on said rotatable part and turning therewith, a worm therein adapted to turn in an internal channel in said bracket and support same and adapted to engage said gear to revolve the shaft.

20. A stopping device for machines, comprising a rotatable brake shaft, a stop device adapted to be actuated by said shaft, a rotatable part of the machine, means for removably supporting said brake-shaft upon said rotatable part so as to permit the swinging of said brake shaft on said support, a worm removably mounted on said rotatable part and adapted to engage a gear on the brake shaft, and said brake shaft adapted to have longitudinal movement in said support.

21. An attachment for machines and the like, comprising a rotatable shaft and means for turning same, a stop device adapted to be actuated by said shaft, an abutment, a traveling member of the machine, and means for connecting said abutment thereto, said shaft having a threaded portion and said abutment having a portion adapted to engage said thread, and said connected members adapted to move in unison whereby a movement of the said rotary shaft member

will cause a corresponding movement of said abutment.

22. A stopping device for machines or the like, comprising a rotatable shaft adapted to have an additional brake controlling movement, a brake shoe controlled by said shaft, a rotary part of the machine to which said shaft is rotatably connected, an abutment having an engagement with said shaft permitting relative movement, a traveling part of the machine to which said abutment is connected, and said abutment adapted when stationary to serve as a fixed abutment for said shaft, whereby a continued movement of the shaft will cause an additional brake controlling movement of said shaft, said abutment being adapted to release the brake upon a movement of said traveling part to an initial position.

23. A stop mechanism for machines comprising a stop, means adapted to move said stop toward a part of the machine to stop the machine and means adapted to compensate for the action of said first-named moving means, a traveling part of the machine adapted to temporarily actuate said last-named means, said moving-means operating to actuate said stop to stop the machine when said last-named means ceases to compensate for the movement of the other.

24. A stop-mechanism for machines comprising a stop, a rotary part adapted to move said stop toward a part of the machine to stop the machine, a rotatable part of the machine to which said shaft is rotatably connected, a traveling part of the machine having means adapted to compensate for the effect of said rotary part to move said stop, said rotary part operating to move said stop to stop the machine when said last-named means ceases to compensate for the action of said shaft to move the stop.

25. A stop-mechanism for machines comprising a stop, a rotary longitudinally movable shaft adapted to move said stop toward a part of the machine to stop the machine, a rotatable part of the machine to which said shaft is rotatably connected, a traveling part of the machine having means adapted to compensate for the effect of said rotary part to move said stop, said rotary part operating to move said stop to stop the machine when said last-named means ceases to compensate for the action of said shaft to move the stop.

26. A stop-mechanism for machines comprising a stop, a rotary longitudinally movable screw-threaded shaft adapted to move said stop toward a part of the machine to stop the machine, a rotatable part of the machine to which said shaft is rotatably connected, a screw-threaded abutment, a traveling part of the machine having means for moving said abutment to compensate for the feed movement of said threaded

shaft therein, said rotary part operating to move said stop to stop the machine when said last-named means ceases to compensate for the action of said shaft to move the 5 stop.

In witness whereof, I have hereunto

signed my name in the presence of two subscribing witnesses.
